UNITED STATES PATENT OFFICE

WILLIAM H. VOGEL, OF HIGHLAND PARK, ILLINOIS, ASSIGNOR TO INTERNATIONAL COMBUSTION ENGINEERING CORPORATION, OF NEW YORK, N. Y., A CORPORATION OF DELAWARE

TRANSPORTER

Application filed June 16, 1927. Serial No. 199,164.

This invention relates to apparatus for transporting finely divided materials such, for example, as pulverized coal.

The invention has to do with that class of transport apparatus in which the material is transported through a line by air under compression, the material being fed from a suitable source of supply to the sphere of action of the pneumatic pressure by means of a feed screw.

In this class of apparatus "blowing back" of the air is to be prevented, and a number of different arrangements have been heretofore proposed for this purpose. In many instances, however, the desired result can only be obtained with heavy power consumption, and it is one of the primary objects of my invention to provide an effective transport device in which the power consumption is relatively small.

Another object of the invention is to provide a feeder for a transport system which is simple and economical to manufacture and which can be readily maintained in effective operating condition.

How the foregoing, together with such other objects and advantages as may herein-after appear, or are incident to my invention, are realized is illustrated in the accompanying drawings, wherein—

Fig. 1 is a side elevation in partial section through a transport feeder embodying my invention;

Figs. 2 and 3 are, respectively, a side and end elevation of one of the units from which the feed screw is built up, and

Fig. 4 is an end elevation of the means provided to prevent "blow back" of the air.

Referring now to the drawings, the reference character A denotes the feeder barrel having an inlet B to receive the material to be transported. The feed screw is indicated at C. Secured over the discharge end of the barrel is a connection D for delivering the material discharged from the screw into the conveyor line E. Powdered coal enters the inlet B from any suitable source of supply through the throat F, and it is advanced through the barrel by the screw to the sphere of action of the compressed air. The com-

pressed air for transporting the coal is admitted to the air chamber 7 at the end of the barrel through the pipe 8, and it discharges into the connection D through a plurality of ports or openings 9 arranged annularly of the discharge end of the barrel.

The screw C is mounted on the shaft 10, and at the end of the screw and within the discharge end of the barrel I provide a segmental disk 11 which rotates with the shaft and screw. In the preferred form of my invention this segmental disk is semi-circular, i. e., it is a half disk, and it is carried on a sleeve-like portion 12 fitting the shaft and keyed thereto. The disk extends transversely of the axis of the shaft preferably at right angles thereto, and the end of the thread terminates adjacent the edge of the disk. The screw preferably has a thread of constant pitch, but the disk has the effect of decreasing the capacity of the last flight of the screw with respect to the other flights.

Under regular operating conditions the apparatus functions substantially as follows. The screw is rapidly revolved and advances the coal entering the inlet end of the barrel. Usually the leading flights of the screw do not run full, for the reason that a portion of the coal is rejected because of the centrifugal action of the rapidly revolving screw. The provision of the disk, however, causes the last flight or so of the screw to become filled with coal particles sufficiently densely disposed as to prevent the air from blowing back. The air admitted through the ports 9, therefore, operates to transport the coal discharged from the end of the barrel into the connection D through the line. I have found it very effective to deliver the air around the coal discharging from the barrel.

By making the disk and its sleeve separately from the screw, I simplify manufacture and am also enabled to replace the disk if it should wear more rapidly than the screw. For substantially the same reasons, I prefer to make up the screw out of a number of elements which are complementary and preferably counterparts of one another. These elements each comprise a sleeve-like

portion 13 having a shoulder 14 at each end and carrying a half thread 15, the ends of which terminate at the shoulders. From an inspection of Fig. 1 it will be seen that these elements can readily be assembled in the form of a screw, the elements being non-rotatably associated with the shaft by any preferred means, such as the locking bolts 16. A screw of any desired length can be made up from these elements, and if any portions of the thread wear more rapidly than others, the same can be readily replaced.

Reverting to the power requirements of the transporter, I have found, by experience, that the provision of the disk enables me to effectively prevent blow back, while, at the same time, the power required for turning the screw is relatively small. This is probably attributable to the fact that only the last flight or so of the screw becomes completely filled. I have also found that the transporter is economical of air and is able to transport for long distances with relatively low air pressures. I also find that I am enabled to use a shorter screw than has heretofore been required.

As the form of the disc 11 may vary according to the material being transported, it is to be understood that the term "segmental disc" is to be liberally construed, that is, it is intended to mean discs which are semicircular, less than or more than semicircular.

I claim:—

35 1. A pneumatic transport device for transporting pulverized coal or other finely divided material comprising a barrel having an inlet, a feed screw in said barrel, a segmental disc at the end of said screw, and means for admitting conveying air beyond said disc.

40 2. A pneumatic transport device for transporting pulverized coal or other finely divided material comprising a barrel having an inlet, a feed screw in said barrel, a segmental disc at the end of said screw, a discharge connection from the barrel to a conveyor line, and means for supplying conveying air to said connection.

45 3. A pneumatic transport device for transporting pulverized coal or other finely divided material comprising a barrel having an inlet, a feed screw in said barrel, a substantially semi-circular disc at the end of said screw and extending transversely of the axis of said screw, and means for admitting conveying air beyond said disc.

50 4. A pneumatic transport device comprising a barrel having an inlet and discharge opening, a shaft extending through said barrel, a screw on said shaft composed of complementary interlocking members each carrying half a screw thread, said members being assembled end to end on the shaft, a segmental disc member at the end of said screw complementary to the end member of

the screw, and means for admitting conveying air beyond said disc member.

5 5. A pneumatic transport device comprising a barrel having an inlet and discharge opening, a shaft extending through said barrel, a screw on said shaft composed of complementary interlocking members each carrying half a screw thread, said members being assembled end to end on the shaft and being counterparts of one another, a segmental disc member at the end of said screw complementary to the end member of the screw, and means for admitting conveying air beyond said disc member. 70

10 6. A pneumatic transport device comprising a barrel having an inlet and discharge opening, a shaft extending through said barrel, a screw on said shaft composed of complementary interlocking members each being composed of a hollow body portion with a shoulder at each end and carrying a half screw thread with its ends terminating at the shoulder, a segmental disc member at the end of said screw complementary to the end member of the screw, and means for admitting conveying air beyond said disc member. 75

15 In testimony whereof I have hereunto set my hand.

WILLIAM H. VOGEL.
